Primary Examiner — Paula Allen Greene(74) *Attorney, Agent, or Firm* — Perkins Coie LLP**CLAIM**

The ornamental design for a headset, as shown and described.

DESCRIPTION

FIG. 1 is a perspective view of a headset showing our new design.

FIG. 2 is a front elevational view thereof.

FIG. 3 is a back elevational view thereof.

FIG. 4 is an outer side elevational view thereof.

FIG. 5 is an opposite outer side elevational view thereof.

FIG. 6 is a top plan view thereof; and,

FIG. 7 is a bottom plan view thereof.
